DISTRIBUTOR HEAD FOR DEHYDRATORS

Joseph M. Hall, Chicago, Ill.

Application April 14, 1938, Serial No. 201,980

17 Claims. (Cl. 281—88)

This invention relates to dehydrating apparatus and more particularly to the head for atomizing liquid products.

One of the objects of the invention is the provision of a new and improved atomizing head for dehydrating apparatuses provided with novel means for discharging the liquid particles therefrom.

Another object of the invention is the provision of a new and improved spraying or atomizing head having novel means for insuring an even distribution of the liquid product on the surface of the rotating elements of the head.

A further object of the invention is the provision of new and improved means for directing the film of liquid along the surface of the rotating head and for causing the same to be discharged therefrom in finely divided particles of substantially uniform size.

A still further object of the invention is the provision of a new and improved atomizing or spraying head that is simple in construction, efficient in operation and that reduces the liquid particles to uniform diameter and discharges them in umbrella form in the dehydrator chamber to have the moisture evaporated therefrom by heated air introduced from above.

Other and further objects and advantages of the invention will appear from the following description, taken in connection with the accompanying drawings, in which—

Fig. 1 is a vertical section of a dehydrating chamber showing the invention in position therein; with parts broken away;

Fig. 2 is a vertical section through the upper portion of the dehydrating chamber and the distributor mechanism, with parts in section and parts broken away;

Fig. 3 is a section on the line 3—3 of Fig. 2;

Fig. 4 is a top plan view of the distributor mechanism shown more or less diagrammatically;

Fig. 5 is a bottom plan view of the lower portion of the dehydrating chamber, shown more or less diagrammatically;

Fig. 6 is a side elevation of a modified form of the distributor mechanism in position on the dehydrating chamber, with parts in section and parts broken away;

Fig. 7 is a vertical section of the dehydrating head, with parts broken away;

Fig. 8 is a section on the line 8—8 of Fig. 7; and

Fig. 9 is a top plan view of the construction

shown in Fig. 6 and shown more or less diagrammatically.

Referring now to the drawings, the reference character 10 designates a dehydrating or desiccating chamber having the cylindrical side wall 11, the upper sloping top wall 12 merging into the flat top wall 13 on which is mounted the distributor mechanism 20. The top wall may be dome-shaped or flat, the form shown is by way of example only.

The lower portion of the chamber walls taper downwardly as at 14 and their lower edges are connected to the top edge of the outer side wall 15 of a circular channel or snail 16 extending around the lower portion of the dehydrating chamber 10 for removing from the chamber 10 the air laden with particles of the dehydrated product. The channel or snail 16 is of gradually increasing cross-sectional area toward its discharge end which leads to the exhaust side of a cyclone separator or collector as is usual in such constructions. The upper edge of the outer wall of the channel is bent inwardly and the wall 14 of the dehydrator is flush with said edge as shown at 17 so that the mixture of air and material may readily enter the channel and the material collecting on the inclined wall 15 may readily slide down into the channel 16.

A suitable cone 18 rises into the lower portion 20 of the dehydrating chamber and is arranged in the axis of the dehydrator for conducting material into said channel or trough 16. The lower edge of this cone extends into the trough and is connected to the outwardly extending portion of the inner wall of the channel 16. This arrangement provides a restricted opening or slot 21 through which the air and material passes into the channel member 16 and at the same time confines the air and material entering said channel from the dehydrator chamber in its movement along said channel.

Since the air introduced into the chamber absorbs moisture from the atomized particles, it will become more or less saturated and the dehydrated material, being hot and in a damp atmosphere, tends to adhere more or less to the walls of the channel 16. It has been found that this may be prevented by increasing the velocity of the air in the channel, especially if the temperature be lowered and its humidity somewhat reduced by directing outside air through the channel.

The air and material entering said channel 55 from the dehydrating chamber are moving right-

handed, as viewed in Fig. 5, and in order to increase the velocity and at the same time somewhat reduce the temperature and the percentage of moisture in the same, means are provided for introducing air directly into the channel 16 from the atmosphere. A conduit 22 is provided for this purpose, Fig. 5.

In order to increase the velocity, an auxiliary fan 23 is provided. A valve 24 is provided for controlling the amount of air introduced.

The distributor mechanism 20 comprises an air distributor 25 for discharging heated air into the dehydrator chamber and a distributor or spray head 30 for reducing the liquid product to finely divided particles.

As shown, the air distributor 25, Figs. 1 and 4, comprises a circular passage or snail 26 gradually tapering from the enlarged end to the opposite or smaller end whereby the pressure and velocity of the air passing around the channel 25 remains substantially uniform. The enlarged portion of the channel is in communication with a conduit 26 which conducts heated air tangentially into the channel 25 from a suitable source of supply. The channel is mounted above and extends around an opening 27 in the top 13 of the dehydrator chamber. The outer circular wall of the chamber rests on the top wall 13 and the inner wall thereof is connected to a connecting wall 28 spaced from the wall 13 to afford an annular space for permitting air to pass from the channel 26 into and through the opening 27.

A depending cylindrical wall or sleeve 29 extends about the opening 27 for directing the air downward into the chamber 10. The air enters 35 the channel 25 tangentially and, as shown, rotates clockwise, as viewed from above in Fig. 1.

The distributor head 30 is supported beneath the cylinder wall or sleeve 29 and is supported by the wall 28. The distributor head and operating mechanism comprises a base plate 31, Fig. 2, supported on the wall 28 on which is mounted the lower section 32 of a fan housing 33 which is coaxial with a depending cylindrical wall or sleeve 290 and to which housing the sleeve is rigidly attached. The housing section 32 has a central opening into which the sleeve 290 extends, as shown more clearly in Fig. 2. The upper section 34 of the fan housing is rigidly connected to a motor casing 35 and has an axial opening therein through which air passing around a channel 36 in the motor casing is adapted to be drawn axially into the fan 37. The fan 37 is of the centrifugal type having the segmental spiral vanes 38 as is usual in such constructions. Since the arrangement of the fan blades are old and well known in the art, it is not thought necessary to illustrate or describe the same more in detail further than to say the air enters axially and is discharged tangentially.

The fan 37 is carried by a spindle 39 having an axial bore 40 through which the liquid product passes to the distributor head 30. The armature 41 of the motor 42 is fast to the spindle for rotating the same. Suitable antifriction bearings 43 and 44 in the motor casing 35 and a similar bearing 45 at the lower end of the sleeve 290, depending from the fan housing 33, are provided for the spindle. A suitable sleeve 46 extends over the upper reduced end 47 of the spindle 39 and is rigidly attached to the motor casing over the antifriction bearing and a suitable gland 48 within the sleeve surrounding the reduced end 47 forms a liquid-tight joint at this point.

5 An adjusting hollow member 49 forced inwardly by a spring 51 engaging a cap member 52 holds the packing or gland 48 in position to form a liquid tight joint about the rotating spindle end. The sleeve 46 has a lateral extension 53 having an axial bore 54 for admitting the liquid product to be dehydrated. A valve 55 regulates the amount of liquid passing through the bore. The sleeve 46 has a reduced portion with lateral openings 56 therein opposite the passage 54 through which the liquid passes to the axial bore 48 of the spindle 39.

10 The motor casing 35 has the passage 36 extending about the same for cooling the motor. The casing is provided with an opening 57 having a filter 58 therein and a hinged closure 59 therefor. A lever 61, held in adjusted position by a quadrant 62, is adapted to hold the closure in adjusted position.

15 Mounted within the fan housing 33 is a partition 63 spaced from the lower section 32 whereby air forced radially outwardly by the curved fan blades 38 will escape through the passage formed by the partition 63 and the lower section of the housing into the sleeve 290. The lower end of the sleeve 290 has a counterbore in which is mounted a bearing retaining plate 64 having an axial bore for receiving the bearing 45 for the lower end of the spindle 39. The bearing retaining plate is provided with a raised portion 65 forming a chamber for the bearing 45. A plate 66 secured to the flanged lower end of the sleeve 290 holds the plate 64 in position. A pipe 68 extending from the exterior of the dehydrating chamber and having its lower end extending into the raised portion 65 is adapted to conduct lubricant to the bearing. The plates 66 and 64 have a plurality of aligned openings 67 through which air delivered by the fan 37 escapes into the air chamber 68, as will presently appear.

20 The sleeve 290 is adapted to have a suitable layer of insulating material 291 extending about the same for preventing the heat of the air from passing downward through the sleeve 290 from injuriously affecting the condensed liquid flowing downward in the bore 48 of the spindle 39.

25 The sleeve 290 is adapted to have a suitable layer of insulating material 291 extending about the same for preventing the heat of the air from passing downward through the sleeve 290 from injuriously affecting the condensed liquid flowing downward in the bore 48 of the spindle 39.

30 A conical casing shield or deflector 69, tapering upwardly, has its flanged upper portion clamped in position by the plate 66 or secured in any other suitable manner and has its lower edge adjacent to the periphery of the rotating distributor head 30. The casing 69 directs the hot air entering through the sleeve 29 from the air distributor 25 downwardly and outwardly across the atomized liquid product discharged tangentially from the head 30. This casing also forms an air chamber 68 for receiving the air delivered by the fan 37. The rotation of the distributor head tends to form a vacuum within the cone or cone member 73 of the head and the air in this chamber will pass through openings 72 in the cone or inverted cap member 73 of the head 30 for relieving the back pressure due to the partial vacuum in this cone. The remaining air escapes outwardly through the slot or space 74 formed between the periphery of the head 30 and the lower edge of the casing 69.

35 The distributor head 30, Fig. 2, comprises the hollow cone or inverted cup or cup member 73 which tapers upwardly and is rigidly attached to the lower end of the spindle 39 as by being screw threaded thereon. The spindle 39 extends into the cone 73 and has a threaded cap 74 thereon. The lower end of the cap 74 is closed and its side wall has outwardly and downwardly extending

openings 75 through which the liquid product passing downward through the passage 40 is projected by centrifugal force and by pressure on the liquid onto the inner surface of the cup.

Cast integral with the lower portion of the cone 73 is a plate 16 which extends radially outwardly and slightly upwardly. Spaced downwardly from the plate 16 is another plate 17 which extends outwardly and slightly downwardly. A plurality of curved vanes 78 are rigid with the two plates as by being cast integral therewith. The lower plate has an axial opening 79 which is closed by a removable closure 81. The lower edge of the cone 73 extends into the space between the plates 16 and 17 and has a plurality of narrow slots 82 in its peripheral edge. These slots are straight and fairly close to each other. They are at an angle to the radius and are so arranged that they extend downwardly and forwardly, that is, in the rotation of the head the outer ends of the slots lead. The slots are so arranged that the upper end of the forward slot is in substantially the same vertical plane passing through the axis of the cone as the lower end of the following slot. By means of this arrangement, the film of liquid product in passing downward along the interior wall of the cone will flow into one or the other of these slots and be thrown from the cone. In other words, each particle of the film will come in contact with one of the slots at some point along the length of the slot. As a result, the liquid product, after being spread out on the inner surface of the cup, will come in contact with the slots throughout their length and will be thrown outward through the slots in finely divided particles in the form of a ribbon or band for each slot. These ribbons of finely divided particles, being in substantially vertical planes, afford a maximum exposure to the hot air revolving about the axis of the dehydrator. In other words, the rotating stream of hot air contacts the ribbon of particles substantially broadside thereby insuring a thorough intermingling of the fine particles and hot air for dehydrating the particles. Furthermore, since the particles are projected from the slots in different horizontal planes, the particles are not so likely to come in contact with one another and coalesce as would be the case were the particles all discharged from one circular edge in a single horizontal plane.

It has been found that this arrangement gives better results, that is, a more uniform size of the dehydrated particles than where the slots are omitted. The inside of the lower slotted edge of the cone or inverted cup is tapered outwardly as at 80, Fig. 2, to facilitate the discharge of the liquid particles from the slots.

The vanes 78 are curved sharply forwardly at their inner ends and are curved but slightly forwardly at their outer ends. In other words, these vanes are concave forwardly with their inner ends curved on a shorter radius than their outer ends. The particles, when they leave the slots 82, are moving at a lower velocity than the vanes 78. Then, in order to prevent splattering of the particles when they strike the vanes 78, these vanes are bowed sharply rearwardly so as to somewhat gradually pick up the particles thrown tangentially outwardly by the slotted edge of the cone thereby greatly reducing spattering and resulting in a more uniform size of particles.

In the operation of the device, the liquid product is conducted from the source of supply under pressure through the valve 55 and passes along 75

the bore 40 of the spindle 39 to the cap 74. The rotating cap and the pressure on the liquid causes the same to be projected onto the interior surface of the cone 73. The rotation of the cone and gravity will cause the liquid to flow in a thin layer down the interior wall of the cone in a layer of gradually decreasing thickness and increasing area. This film will be intercepted by the slots and the liquid forced through the slots will be discharged tangentially outwardly and will be picked up by the curved vanes 78. The liquid will be thrown gradually outward and as the blades 78 gradually increase in width and circumference, the surface is much more extensive than the interior of the cone and the liquid spreads out in a thin film over the blades 78 and is thrown from the same in very fine particles in umbrella form in the dehydrator.

Air entering the fan 37 through the passage 36 is directed downwardly through the sleeve 290 around the spindle tending to cool the same and to cool the bearings therefor and then passes through the passages 67 into the chamber 68 and from the chamber part of it passes through the passages 72 into the cone 73 for reducing the back pressure within the cone.

Simultaneously, heated air entering the air distributor 25 will be caused to rotate either in the opposite or in the same direction as the head 30. Preferably, as in the form of the construction shown, the air and head rotate in the same direction. Better results may be obtained by having the air and head rotate in the same direction since there is no such violent turbulence and uneven mixing of the air and liquid particles as when they rotate in opposite directions.

The air from the distributor 25 passes downwardly through the sleeve 29 whirling as it descends. The shield 69 directs the same, still rotating, outwardly and downwardly across the periphery of the head and mixing with the finely divided particles will dehydrate the same. The dehydrated particles will be exhausted from the chamber through the channel 16 and conduit 83 and will pass to the separator.

In Figs. 6 to 9 is shown a modified form of liquid distributor mechanism. In this form of the apparatus shown in these figures, the air distributor is a different construction from that shown in Fig. 1. In this form of construction, a circular air chamber 250 is provided into which heated air is introduced tangentially through the pipe 260 (Fig. 9). The chamber 250 is mounted on the top wall 13 of the distributor chamber, which wall may constitute the bottom wall of the air chamber.

As shown, the distributor supporting base 85, seated on the air chamber 250, has a motor case 86 mounted thereon. An electric motor 87 is mounted within the casing, the armature 88 of which is fixed to a spindle 89 (Fig. 6). This spindle has a bore 91, through which the liquid product passes from a suitable source of supply to the sprayer or atomizer head 92, as will presently appear. The motor casing has ventilating openings 93, and a fan 90 on the armature shaft draws air into the motor for cooling the same.

Suitable breather openings 930, with filter 940, are provided on the motor base for supplying air to the distributor head to relieve the back pressure therein, as will presently appear.

A suitable connector 96 is provided to which the conduit is attached for conducting the liquid product to the bore 91 from a suitable source of supply. A lubricating tube 66, extending down

within the sleeve 390 for oiling the bearings, is also provided.

The arrangement of the bearing and construction of the head 92 differs from the form shown in Fig. 2, as will now be described. In this form of construction the head 92 is more or less concave, opening downwardly, and comprises a head casting in the form of an inverted cup 97 concave on its lower side and having an axial upstanding hollow stem portion 98 providing a chamber 99 therein. The chamber 99 has its upper end provided with means for forming a sliding interlocking or spline connection with the lower end of the spindle 89, as shown at 101 in Fig. 8.

The head is held in position by bearings 102 and 103, the inner members of which are secured to the stem and the outer member to a sleeve 104. The sleeve 104 has a channel 105 in its lower end for receiving excess oil from the bearing. The sleeve 104 is detachably connected to a plate 106 integral with or rigidly connected to the sleeve 390. The sleeve 104 and stem 98 have cooperating rabbets in which are seated the thrust bearings 102 and 103. The threaded rings 107 and 108 engaging, respectively, the internal threads in the sleeve 104 and the external threads on the stem 98 hold the bearings firmly seated in the rabbets.

The inner members of the ball bearings clamp an annular guard 109 against the ledge 110 formed by the rabbet on the stem. The guard 110 extends into the channel 105 for directing oil from the bearings into the channel.

A shield 120 has its inturned upper end clamped to the plate 106 and extends downwardly and outwardly for directing the hot air from the distributor 250 passing downward through the sleeve 125, downward and outward across the outer edge or peripheral edge of the distributor head for mixing with the liquid particles projected tangentially outward from the rotating head for dehydrating the same.

A cup-shaped shield 115 is provided beneath but adjacent to the head 92. The peripheral edge of the member 115 is closely adjacent to the head at the upper end of the slots 113 and any liquid that may fall on the shield 115 during the operation of the device will be projected outwardly by centrifugal force and by the air from the chamber 99 onto the lower portion of the head. The slots 113 are narrow but are wide enough for the liquid in the film on the head to pass through the slot and be projected from the edges of the slots, substantially throughout their lengths, in the form of a band or ribbon of finely divided particles.

The stem 98 is provided with passages 111 for conducting the air flowing through the motor and sleeve 390 into the chamber 99 for conducting air to the interior of the cup member to relieve the back pressure due to the partial vacuum formed by the centrifugal action set up by the rotating head. These passages diverge downwardly whereby the centrifugal action on the air therein assists in causing the air to flow through these passages. A plurality of outwardly and downwardly extending openings 112 are provided for the escape of the air and liquid from the chamber 99. The lower edge of the head 92 has narrow slots 113 fairly close together which extend downwardly and forwardly. The slots are so arranged that the lower end of each precedes its upper end in the rotation of the head and the top end of the advancing slot is in sub-

stantially the same vertical plane extending through the axis of the head as the lower end of the following slot so that the liquid, even though it should flow downwardly in a vertical plane passing through the axis of the head, will flow into the following slot. The blades 114 formed by the slots 113 are tapered outwardly and downwardly from its inner side so as to increase the centrifugal action.

5 The shield 115 is provided for forming with the head 92 a passage 116 for confining the liquid therein. The shield terminates in a zone above the plane of the slots 113 and closely adjacent thereto. The shield is secured in position by screws 117 or the like which extend through the bottom of the chamber 99.

10 The head is rotated at high speed and consequently tends to out-travel the liquid thrown onto it from the chamber 99. In order to prevent this overrunning, the inner surface of the head has attached thereto comparatively thin narrow strips 118, Figs. 6 and 7.

15 The provision of the narrow slots 113 angularly arranged has been found to give a great uniformity in the size of the dehydrated particles, as pointed out above. Rotating the head and dehydrating air in the same direction is also conducive to uniformity in size of the individual particles since there is not such wild turbulence of the air as when they rotate in opposite directions. In other words, a smoother action with a minimum of coalescing of the particles ensues.

20 The head 92 may be of any suitable size. The 35 dimensions and form of the different parts may vary within wide limits and may also vary with the particular substance to be dehydrated. It has been found that where milk condensate is treated, a head sixteen inches in diameter and having slots one and one-quarter inches long, one-eighth inch wide and arranged at an angle of about 60 degrees to the lower edge of the head and the head rotated at about 3400 R. P. M. give satisfactory results.

25 It is thought from the foregoing, taken in connection with the accompanying drawings, that the construction and operation of my device will be apparent to those skilled in the art and that changes in size, shape and proportion 40 may be made without departing from the spirit and scope of the appended claims.

30 I claim as my invention:

1. In a liquid product dehydrating apparatus, 45 a distributor head comprising an inverted cup member having its peripheral edge provided with a plurality of narrow slots arranged at an angle to a vertical plane passing through the slot and the axis of the head, means for delivering a liquid product to the interior of the inverted cup member, means for rotating the head, for atomizing said liquid product, a casing surrounding the upper portion of said cup member and tapering upwardly, and means for directing a blast of gaseous drying medium downwardly over the outer edge of said casing for dehydrating said liquid product.

50 2. In a liquid product dehydrating apparatus, 55 a distributor head comprising an inverted cup member tapering upwardly and having its peripheral edge provided with a plurality of narrow open ended slots arranged at an angle to a vertical plane passing through the slot and the axis of the head, means for rotating said head in a direction that the lower ends of the 60 slots lead the upper ends thereof, means for

discharging a liquid product on the interior face of the head, and conduits for conducting air to the interior of said cup member for relieving back pressure therein during its operation.

3. In a liquid distributor mechanism for dehydrators, a head comprising an inverted cup member having its lower edge provided with narrow slots arranged at an angle and at such distance apart that a vertical plane through the axis of the head passing through the upper end of the advancing slot will pass through the forward end of the following slot, said slots having free open lower ends, means for rotating said head in such a direction that the upper ends of the slots follow the lower ends thereof, means for rotating said head, means for projecting a liquid product on the inner surface of said head, a cone-shaped deflector extending over said head and having its lower edge adjacent the outer edge of said head, and means for directing a stream of heated gaseous drying medium downwardly onto said deflector, said deflector causing said air to flow downwardly and outwardly across the outer edge of said head for atomizing and dehydrating said product.

4. In a liquid product dehydrating apparatus, a distributor head comprising an inverted cup member having its peripheral edge provided with a plurality of narrow slots opening downwardly, means for rotating the head, means for projecting a liquid product onto the interior of said head, means for delivering air under pressure within said head, a cone-shaped deflector over said head, and means for directing a stream of heated air downward onto said deflector for causing the same to flow downwardly and outwardly across the outer edge of said head.

5. In an apparatus for dehydrating liquid products, a hollow spindle for conducting liquid products along the same, a distributor head on the lower end of said spindle, said head comprising an inverted cup-shaped member having its lower edge provided with a plurality of comparatively narrow slots open at their lower ends, said slots being arranged at an angle to the axis of said head, means for rotating said head in such a direction as to cause the upper ends of said slots to follow the lower ends thereof in the rotation of said head, the upper end of each slot being substantially in a vertical plane through the radius of said head, said spindle extending into said head and having radial openings therein through which said liquid product is discharged, a cone-shaped casing for said head, and means for directing a mass of heated air downwardly against said casing for causing the same to flow downwardly and outwardly across the peripheral edge of said head.

6. A distributor head for dehydrators comprising a cone member having a slotted lower edge, a pair of radially extending plates rigid with the cone member and spaced apart, curved blades between said plates, means for conducting a liquid product to the interior of the cone, and means for rotating said head.

7. In a dehydrating apparatus, an inverted cup member having its lower edge provided with a plurality of slots each arranged at an angle to a vertical plane through the slot and axis of the cup, the lower ends of said slots opening forwardly, a pair of plates spaced apart and rigidly connected together and to said cup, blades rigidly mounted between said plates and having their ends curved forwardly, means for delivering a liquid product to the interior of

said cone, and means for rotating said head at high velocity whereby the liquid product will flow down the inner wall of said cup and will be discharged through said slots in a uniform band of liquid particles onto the concave side of said blades and be discharged from the outer end of said blades in a band of atomized particles.

8. In a dehydrating apparatus, a distributor head, means for rotating the same, said head comprising an inverted cup having its lower edge slotted with each slot extending at an angle to a vertical plane through the slot and axis of the cup, the lower ends of the slots being in advance of the upper ends and the lower end of one slot being in a vertical plane through the axis of the cup and the upper end of a leading slot whereby all liquid product flowing down the inside of said cup will be intercepted by some portion of one of said slots and said product discharged from said slots in bands, a plurality of curved blades carried by said head and arranged radially outwardly from said slots having their inner ends curved forwardly on a comparatively short radius for intercepting said bands, and their outer ends curved forwardly on a longer radius for discharging said product collected from said bands and in turn discharging the same in bands of finely divided particles in vertical planes tangent to the path of movement of the outer ends of said blades.

9. In a dehydrating apparatus, distributing mechanism comprising a hollow spindle, a motor having an armature fast on said spindle for rotating the same, an air passage around said spindle, a sleeve surrounding the lower end of the spindle, a distributor head on the lower end of said spindle, said head comprising an inverted cup provided with air passages in its upper end and having angularly arranged slots on its lower edge, the lower end of said spindle having downwardly and outwardly extending openings through which liquid flowing through said spindle may be discharged onto the interior of said cup and flowing downwardly by gravity and centrifugal force be thrown from the marginal edges of said slots in bands of finely divided particles, a plurality of vanes rotating with said cup, arranged radially outwardly from said slots and having their inner ends curved forwardly on a relatively short radius for intercepting said bands without an abrupt impact and having their outer ends curved forwardly on a longer radius for discharging said product in a band of atomized particles, a fan on said spindle for causing air to flow through the air passage around said motor and downwardly through the passages in said cup for preventing back pressure therein, a cone-like shield above said distributor head, means for causing heated air to flow downwardly in a spiral over said shield in the same direction as the rotation of said head for thoroughly mingling the heated air with said particles for dehydrating the same.

10. In an apparatus for dehydrating liquid products, distributor mechanism comprising a spindle, means for rotating said spindle, said spindle having an axial passage extending therethrough for the passage of a liquid product, a chamber at the lower end of the spindle, a distributor head having a surface curved in cross section on the lower end of said spindle, passages extending outwardly from said chamber within said head for the discharge of liquid product contained in said chamber onto said curved surface, ribs on the inner surface of said cup ex-

tending from the axis to the peripheral edge thereof for causing the film of liquid on the inner surface of said cup to rotate at the speed of said cup, a cylindrical sleeve surrounding said spindle, an air chamber in communication with said sleeve, a conduit for conducting hot air to said air chamber and constructed and arranged to discharge the same tangentially therein for causing the air to rotate spirally downwardly through said sleeve around said head and rotating in the same direction as said head, said head having slots in its lower edge arranged at an acute angle to the direction of movement with the lower ends of said slots leading, the upper end of any one of said slots being in a vertical plane through the axis of the head and the lower end of the following slot.

11. In a dehydrating apparatus, a distributor head having a recess therein through which a liquid product is adapted to be delivered to the interior of said head, means for rotating said head for discharging said liquid therefrom in finely divided particles, a stationary air deflector over said head, means for delivering heated air onto the exterior surface of said deflector, said deflector having cone-shaped deflecting surfaces for deflecting said heated air outwardly and downwardly across the peripheral edge of said head for dehydrating said particles, and air passages diverging downwardly in said head for conducting air to the interior of said head for relieving the back pressure therein.

12. In a dehydrating apparatus, a distributor head comprising an inverted cup member having slots in its lower edge angularly arranged relative to its direction of rotation, the lower ends of said slots leading the upper ends thereof during rotation of the head, a supporting upstanding vertical stem having a recess therein for receiving liquid product for treatment, passages leading from said recess to the interior of said head, an inverted cup shield member within said cup member spaced downwardly from the upper wall of said cup member, the peripheral edge of said member being adjacent the upper ends of said slots, a cylindrical support extending about said stem, antifriction bearings having one portion rigidly secured on said stem and the other on said support, said stem having an axial opening provided with means for interlocking connecting said stem to a rotating spindle.

13. In an apparatus for dehydrating a liquid product, a distributor head comprising a rotatable spindle, an inverted cup-shaped member on said spindle and rotatable therewith, said spindle having a passage extending lengthwise thereof for conducting a liquid product to the interior of said member, said member having slots in its lower edge arranged at an acute angle to the direction of movement and with the upper end of any one of said slots in a vertical plane through said spindle and the lower end of the following slot, a cone-shaped deflector suspended from said head, means for introducing air under pressure into said cone and the upper portion of said member for relieving back pressure therein during the operation of said head, said deflector having its lower edge spaced slightly from said head to provide a circular opening for the escape of a portion of said air, and means for directing a spirally moving stream of air against said deflector for causing the same to flow downwardly and outwardly across the peripheral edge of said head for desiccating said product.

14. In a liquid product dehydrating apparatus, a distributor head attached at its upper end and comprising an inverted cup member tapering toward its upper end, having its axis vertical and having its circular lower edge provided with a plurality of open ended narrow slots arranged at an angle to a vertical plane passing through the slot and the axis of the head, a conduit having lateral apertures in its lower end for delivering a liquid product to the interior of the inverted cup axially thereof, means for rotating said conduit and head for discharging said liquid from the lower ends and intermediate portions of the slots, means for conducting air to the interior of said cup member during its operation, and means for causing a current of heated air to flow downwardly and outwardly across said peripheral edge for dehydrating said product discharged from said head.
15. In a liquid product dehydrating apparatus, a rotating distributor head comprising an inverted cup member having its peripheral edge provided with a plurality of open ended narrow slots opening downwardly said slots being arranged at an acute angle to the plane of rotation of said head, a hollow member for conducting a liquid to said distributor head, means for closing the lower end of said hollow member, said means having laterally opening apertures, means for rotating said head and hollow member for projecting a liquid product onto the interior of said head, said head discharging said product in finely divided particles therefrom in an umbrella form, means for delivering air under pressure within said head, and means for directing a current of gaseous heating medium downwardly and outwardly across the peripheral edge of said head for assisting in atomizing and for dehydrating said particles.
16. In a liquid distributor mechanism for dehydrators, a head comprising an inverted cup member, having its lower edge provided with narrow slots open at their outer ends only and arranged at an angle and at such distance apart that a vertical plane through the axis of the head passing through the upper end of the advancing slot will pass through the lower end of the following slot, means for rotating said head in such a direction that the upper ends of the slots follow the lower ends thereof, means for projecting a liquid product on the interior of said head, means for rotating said head for discharging said product from the end portions of said slots, and means for delivering air under pressure to the interior of said cup member.
17. A rotating distributor head for dehydrating apparatus comprising an inverted cup member supported from its upper end and tapering toward its upper end and having narrow open ended slots in its peripheral edge opening downwardly, each slot being arranged at an acute angle to its plane of rotation and having its upper end in substantially a vertical plane passing through the axis of the head and the lower end of a following slot, a hollow rotating spindle on which said cup member is mounted, said spindle extending into said cup member and having its lower end closed and provided with downwardly and outwardly extending openings therein rotatable with said spindle for discharging a liquid product introduced through said hollow spindle, and means for directing a current of heated air downwardly across the outer margin of said head for desiccating said product.
